US00D707214S

(12) United States Design Patent
Reivo et al.

(10) Patent No.: US D707,214 S
(45) Date of Patent:  Jun. 17, 2014

(54) HANDSET

(71) Applicant: Nokia Corporation, Espoo (FI)

(72) Inventors: Tuomas Reivo, Espoo (FI); Terence Tan Han Yang, Espoo (FI)

(73) Assignee: Nokia Corporation, Espoo (FI)

() Term: 14 Years

(21) Appl. No.: 29/437,578

(22) Filed: Nov. 19, 2012

Related U.S. Application Data

(63) Continuation of application No. 29/431,084, filed on Sep. 4, 2012, now Pat. No. Des. 693,787.

(57) CLAIM

The ornamental design for a handset, as shown and described.

DESCRIPTION

FIG. 1 is a perspective front view of a handset showing our new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

The broken line showing of the environmental structure of the handset in the figures is for illustrative purposes only and forms no part of the claimed design.

1 Claim, 5 Drawing Sheets
